SCM Corporation, New York, N.Y.

Filed Aug. 28, 1974, Ser. No. 501,120

Term of patent 14 years

Int. Cl. D18—99

U.S. Cl. D64—11 B

The figure on the drawing is a front perspective view of a control handle for an office machine showing my new design.

The right side of the control handle is a mirror image of the left side and the bottom and back are unadorned.

The characteristic feature of my design resides in the ornamentation on the front surface.

I claim:

The ornamental design for a control handle for an office machine, as shown and described.
